CONTAINER CAP CONSTRUCTION

Augustine W. Campbell, Detroit, Mich.

Application February 23, 1935, Serial No. 7,697

4 Claims. (Cl. 221—60)

The present invention relates broadly to containers having removable caps and more particularly to deformable containers such as collapsible paste or cream tubes having screw threaded caps which may be removed to permit discharging the contents from the tube. It will here be understood, however, that other types of containers may well be equipped with the means forming the present invention, it being within the purview of this invention to so equip bottles, tin cans, etc.

The principal object of the present invention is to provide means cooperating with the container and with the cap for preventing the loss of the cap and formed to provide a spring action whereby the cap may be moved to or from the threaded neck of the container with which the cap cooperates, with a spring movement, as desired, the means being so constructed as not to interfere with free rotation of the cap upon the threaded neck of the container, and also being constructed so that the cap cannot be disconnected from the means, nor can the means be disconnected from the container when the cap is unscrewed.

The foregoing and other objects, together with their attendant advantages, will be apparent as the invention becomes better understood by reference to the accompanying specification and drawing forming a part thereof, it being understood that changes may be made in the various details and the manner of operation within the scope of the appended claims without departing from the spirit of the invention. In this drawing,

Fig. 1 is a side elevation of a portion of a container having a cap held thereon by the means of the invention, the cap being shown in section;

Fig. 2 is a sectional view through line 2—2 of Fig. 1;

Fig. 3 is a top plan view wherein the means represents a modification of the means of Figs. 1 and 2.

Referring to the drawing, there is illustrated a container 1 having a neck provided with a lower portion 2 and terminating in a threaded portion 3 which is of considerably less diameter and length than the portion 2. For closing the container there is provided a cap 4 having a bore at 5 substantially of the diameter and length of the neck portion 2, though slightly greater in both dimensions, and having a counter bore internally threaded to cooperate with the threads of the threaded portion 3 of the container neck.

The bore 5 of the cap is provided with a bevel

or fillet at 7 which cooperates with the bevel 8 between portions 2 and 3 of the container neck and with the side wall of the portion 2 of the container neck to pilot the cap into place so that the action of threading the cap onto the threads 3 is facilitated.

The cap dimensions are such that excess material found around the mouth of the container at the neck portion 3 will be entrapped within the cap and will not be carried down by the cap to 10 the outside thereof; and to facilitate this action relatively deep and long slots 9 are provided in the neck portion 3 whereby excess material around this portion will be worked back into the container as the cap is threaded in place.

For non-removably securing the cap to the container and for carrying the cap there is provided a wire 14, bent in a loop as illustrated so that a bight portion 15 encircles the cap, being received within the groove 16 of the latter, and 20 the ends 17—18 of the wire are inwardly bent as shown to be received within the holes 19 and 20 of a lug 21 formed on the container.

It is here observed that the holes 19 and 20 are not co-axial, and that the ends 17—18, as originally manufactured, are non-aligned, as in Fig. 2.

When the cap is in the position of Fig. 1 the cap will be loose within the bight 15 of the wire and it can be threaded on or off the container neck freely and without being interfered with by the 30 wire.

When the cap is swung towards the open position (not shown), the wire will be tensioned as the cap and wire pass an over-center position, and such tension will cause the wire and the cap carried thereby to spring with a snap action into open position after it had been moved partially towards such position and be held in open position under spring tension. When the cap is to be returned to the closing position, the initial movement of the cap and wire, caused manually, will overcome the spring tension in the wire, and the wire, carrying the cap, will snap into the closing position.

If desired, the wire may be formed with a cross loop at 23, Fig. 3.

It will be observed that an important consideration is the fact that the formation of the wire does not interfere with the action of threading 50 the cap down into place.

It is observed that the underlying and basic concept of the invention is the provision of offset or non-aligned holes 19—20 for the offset, or non-aligned ends of the wires 17—18, and this charac-

terizes the construction here shown from prior known constructions.

Though I have described the invention with some degree of particularity, it is here observed that alterations may be made to some extent and therefore I here reserve the right of changing the form of the details of construction or otherwise altering the arrangement of the correlating parts without departing from the spirit of the invention or the scope of the appended claims.

Having thus described my invention, what I claim as new and desire to secure by United States Letters Patent is:

1. An improved cap retaining means for containers having a neck portion through which the contents of the container may be discharged and a cap cooperating with the neck portion, said neck and cap being screw-threaded and the cap having an external annular groove, and the container having an external lug, comprising a resilient retaining wire looped to provide a bight disposed in the cap groove and encircling and freely jour-

nalling the cap, and having ends disposed in holes of the lug, there being two separate holes, with the axis of each being out of line with the axis of the other, the offset alignment of the holes with the ends of the wire therein functioning to move the member and the cap carried thereby with a spring action in opening or closing movement.

2. The combination of a container neck having external threads, an internally threaded cap therefor, a looped wire link having a bight enclosing the cap and freely journaling it therein, a lug on the container provided with two separate and distinct out-of-line holes, the two ends of the link being bent towards each other and being disposed separately in said holes.

3. A combination of the character described in claim 1 where the lengths of the wire halves from neck to hole are unequal.

4. A combination of the character described in claim 2 where the lengths of the wire halves from neck to hole are unequal.

AUGUSTINE W. CAMPBELL.
